UNITED STATES PATENT OFFICE.

FREDERICK B. THURBER, OF PROVIDENCE, RHODE ISLAND, ASSIGNOR TO TILDEN-THURBER CORPORATION, OF PROVIDENCE, RHODE ISLAND, A CORPORATION OF RHODE ISLAND.

DESIGN FOR A SHAVING-BRUSH HANDLE.

46,145.

Specification for Design.

Patented July 21, 1914.

Application filed March 9, 1914. Serial No. 823,585. Term of patent 14 years.

To all whom it may concern:

Be it known that I, FREDERICK B. THURBER, a citizen of the United States, residing at Providence, in the county of Providence and State of Rhode Island, have invented a new, original, and ornamental Design for Shaving-Brush Handles, of which the following is a specification, reference being had to the accompanying drawing, forming part thereof.

Figure 1 is a plan view showing the side or relatively flat surface of the brush handle, the contour of the bristles being shown in

dotted lines; and Fig. 2 is a view at right angles to the plan of Fig. 1, showing the edge or thin face of the brush handle.

The design consists in the shape or configuration of the brush handle as an entirety.

I claim:

The ornamental design for a shaving brush handle, substantially as shown.

FREDERICK B. THURBER.
